DOUBLE DIVIDER

Jack Taylor, Yavapai County, Ariz.

Application April 11, 1942, Serial No. 438,641

2 Claims. (Cl. 33—189)

This invention relates to double dividers used by sheet metal workers in various kinds of work in laying out patterns and stretch-out sheets and has for its objects:

First, the provision of a double divider having two calibrated flat beams extensible from a central body portion and provided with means for engaging the position of the beams in said body, together with marking or indicating points at the outer end of said beams, and marking or indicating point at a definite position on said body. The body portion and holders for the indicating points at the ends of the beams are all designed so that the device will lay flat on sheet metal work or on layout sheets.

An additional object is to provide means for fine adjustment of the end marking points within limits independently of the beam setting.

A still further object is to provide a divider, as above described, having vertically adjustable measuring points adapted to slide within grooves in a guiding T so that by using one of the end points as a marker and the other two points as guides, the marking point can be made to describe elliptical curves corresponding to the settings of the other two points as they move in the horizontal and vertical grooves of said T guide.

Other objects will appear hereinafter.

I attain the foregoing objects by means of the device illustrated in the accompanying drawing in which,

Figure 1 is a plan view of the divider;

Figure 2 is an elevational view thereof;

Figure 3 is a section taken substantially on lines 3—3, Figure 2;

Figure 4 is an end elevation of left end as shown in Figure 2;

Figure 5 is a section taken substantially on line 5—5, Figure 1;

Figure 6 is a section taken substantially on line 6—6, Figure 1, drawn on a somewhat enlarged scale;

Figure 7 is a plan view of a demountable type of T guide which is readily adaptable to use with the above divider for purposes hereinafter described; and

Figure 8 is an end view of the vertical member thereof.

Similar numerals refer to similar parts in all the views.

The body or central portion of the entire beam compass is indicated by numeral 2. This consists of a metallic rectangular shaped block of metal having longitudinal V or dovetailed shaped

slots 3 and 4 respectively, cut throughout its middle portion. These slots are proportioned to receive the beams 5 and 6 respectively, with an easy, sliding, working fit. Two set screws 7 and 8 are provided on the rear face of the body 2 to hold these beams in any longitudinal position desired. Extending from the right hand end of the body portion as view in Figure 1 is a marking point supporting lug 10, carrying the marking point 11. This is brought out so as to be aligned longitudinally with the markers in the end of each of the beams 5 and 6.

The markers at the ends of the beams are made alike and with interchangeable parts and consist of a screw portion 12 having a knurled knob 13 at the top and a hardened steel trammel point 14 at the bottom. The threaded portion is received by a collar 15 attached to a supporting bracket 16 which is attached to and made part of a block 17 and this, in turn, is attached to and longitudinally adjustable relative to the end of the beam to which it is attached.

Supporting and adjustment means for these blocks on the sliding beam is shown particularly in Figures 1 and 6. Here it is noted that there is a screw 20 which extends longitudinally through a threaded hole on one side of the center of block 17. A threaded collar 22 forms a lock nut for this screw. The inner end of the screw is provided with an annular groove 23 and a vertically extending pin 24, pressed into a hole 25, serves to retain the screw 22 in place in the end of the beam while the threaded portion works in block 17 to or from the beam end. An additional longitudinal guide member consists of a pin 26 set into block 17 and sized to a working fit in a hole 27, drilled into the end of the beam.

Each of the marking points is provided with a set screw 30 so that after its height relative to the work on which the device is placed is set, this may be set and maintained. The marking point supporting blocks 17 at the end of each beam, are substantially the same, being made right and left accordingly, except that since beam 6 works within the lower portion of the block 2 and beam 5 in the upper portion, the height of the bracket portions 16 varies so that the collars 15 will be on the same level. This permits the trammel screws and points to be made the same and to be interchangeable.

The guide T shown in Figures 7 and 8, is used with the divider in marking and laying out curves. This consists of a central portion 33

having horizontal detachable arms 34 and 35 on each side, and a vertical piece 37 extending at right angles from its middle. The removable portions are held onto the central portion by removable pins 36 at each joint. A horizontal guide groove 45 extends across the face of the horizontal bars and central portion, and a vertical groove 46 extends along the top of the vertical piece 37 joining an aligned groove in the central portion 33 which intersects the horizontal groove 45. Aligning indicating tabs or points 41 are formed at the end of each of the three arms, with their points registering with the bottom of grooves on the faces of these arms. Long or short arms may be fitted onto the central portion 33, depending on the dimensions of the arc to be drawn.

In use, the blocks 17 supporting the trammel points at the ends of the beams are ordinarily set up tight against the beam ends so that the readings on the scales 31 on the beams may be read directly from the right edge of block 2, if desired. Where, for example, measurements are to be transferred from a triangulation layout to a stretch-cut sheet, the set screws 7 and 8 are released so that the beams will slide and the major or longer distances taken between the trammel point 11 on the body 2 and the trammel at the end of beam 6. Set screw 8, being adjusted when necessary to maintain this distance after transference of the measurement. At the same time the minor measurements of the triangulation are taken between trammel point 11 and the point at the end of beam 5. The advantage of this type of work is that it eliminates the use of two ordinary dividers; otherwise one divider must be used for the major measurements and another for the minor measurements. If this is not done the worker is very likely to become confused with the last preceding measurement and an erroneous variation in the curve being produced may occur. Even when two dividers are used there is a chance of confusing them where the difference between the transfer measurements becomes slight.

To those familiar with this type of layout work the advantages afforded by this device will be readily appreciated. In making measurements the body of the device is laid flat on the layout, the base 29 supporting the rear edge of body 2; the trammel points are easily visible and measurements can be made exactly. When a measuring beam is set, the corresponding set screw (7 or 8) turned up and the other measurement is then taken. Both may then be transferred to the stretch-out sheet. Each measurement may be taken without disturbing the other. Where the use of scales 31 is unnecessary and the difference in successive measurements is small use is made of the adjusting screws 20 at the ends of the beams.

Other uses include the marking of dimensions

where a certain width of sheet by one end of the divider and the marking of the lap by using the other end of the divider. Either end of the divider can be used as the marking arrangement where the device is used as a beam compass. It is understood that each of the trammel points may be replaced by a pencil of suitable material or a soapstone marker; these being held in either case by the set screws 30.

10 Where the device is used to draw an irregular or elliptical curve the guide T is set on the work with the horizontal points 41 at either end of the horizontal guide bar 40 aligned with the major axis of the curve. Point 41 on the vertical bar 15 of the T is made to coincide with the minor axis of the curve.

The trammel point at the left end of the divider is placed in the groove 45 at its intersection with groove 46. Point 11 is placed in the groove 45 at a focal point to the right of this intersection. The right hand marking trammel is then moved following the curve while these points slide in the grooves. The point at the left end of the device moving down the groove 46 and the point 11 moving to the left along groove 45. The result is that the marking point at the right describes an elliptical curve corresponding to the settings of the other two points on the major and minor axes as represented by grooves 45 and 46 respectively, in the guiding T.

I realize that to those familiar with the art numerous modifications and changes may be suggested from the foregoing, all of which, however, might well remain within the spirit of the invention. Therefore, I wish to be limited to the following claims:

I claim:

1. A double divider comprising in combination a supporting body having a marking point affixed to its front edge, a downwardly depending rear base portion substantially in the same plane as said marking point, beams supported on said body so as to be longitudinally slidable therein, removable trammel points adjustably supported at the ends of said beams and means for separately locking said beams in any desired extended position.

2. A double divider comprising, in combination, a centrally positioned body portion having longitudinally extending dovetail slots cut in its top and bottom respectively, its bottom formed to lie flat on layout work and a removable trammel point attached to its front edge, slideable calibrated beams slidably operative in said slots in said body, trammel point blocks attached to the ends of said beams, means for longitudinally adjusting said blocks relative to the ends of said beams, removable trammel points threaded into said blocks, and lock screws operative in said block adapted to retain either of said beams in position in said block.

JACK TAYLOR.
